CHARLES V. LOGWOOD, OF SAN FRANCISCO, CALIFORNIA.

RADIO RECEIVING SYSTEM.

Application filed March 10, 1921. Serial No. 451,217.

The present invention relates to improvements in the arrangement and connections of electrical apparatus at the receiving station of a radio system and particularly a system of this kind in which a thermo-ionic vacuum tube is used as the Hertzian wave detector.

An object of the invention is to amplify the effect of the received waves upon the current in the telephone or other receiving circuit, to increase the loudness and definition of the sounds in the telephone or other receiver, whereby more reliable communication may be established, or a greater distance of transmission becomes possible.

10 A further object of the invention is to provide a radio receiving system for receiving signals from continuous wave transmitting stations, without resorting to the production of beats in the receiving circuit. One widely used system of radio reception, known as the heterodyne system, involves the use of beats produced by establishing an oscillating circuit having a frequency slightly different from the frequency of the received signals, 20 so that incoming signals produce beats which are heard in the telephones. In accordance with my invention, oscillations in the receiving circuit are established only when the signal is coming in and these oscillations are 25 amplified and the circuit of the amplified oscillations interrupted to produce the sounds in the telephones. The frequency of interruption is within the range of audibility, so that when signals are coming in, a note is 30 heard in the telephones, but when no signals are coming in, there is no appreciable sound in the telephones.

Generally considered, the system of my invention comprises a thermo-ionic vacuum 40 tube, having interlinked grid and plate circuits, which oscillate only upon the receipt of a signal and which are provided with means for changing them rapidly from oscillating circuits to non-oscillating circuits during the 45 receipt of a signal, whereby the loudness and definition of the sounds in the receiver are greatly increased. The invention further contemplates further coupling of the grid and plate circuits whereby variations in the 50 current in the plate circuit caused by variations in the grid circuits are employed to further amplify the variations in the grid circuit, thus further amplifying the variations in the plate circuit.

55 The plate circuit is inductively coupled to

the grid circuit, and constitutes a feed back circuit, in which the oscillations are of the same frequency and in phase with the oscillations in the grid circuit, thereby amplifying the oscillations in the grid circuit. Thus, 60 during the brief interval of time that the grid circuit is closed, incoming oscillations causing oscillations of considerable amplitude are built up in the grid circuit and in the plate circuit and these oscillations cease 65 abruptly when the grid circuit is opened by the interrupter.

An incoming signal from a continuous wave source causes a change in grid potential, causing a corresponding change of potential in the plate circuit, which change of potential is instantaneously fed back into the grid, in the same phase and frequency as the incoming signal. The coupling between the grid circuit and plate circuit is such that 70 a self-oscillating grid circuit is not produced and so that the energy in the circuit diminishes instantly on the stopping of the signal.

The invention possesses other advantageous features, some of which, with the foregoing, will be set forth at length in the following description where I shall outline in full, those several forms of receiving systems, embodying my invention, which I have 80 selected for illustration in the drawings accompanying and forming part of the present specification. In said drawings I have shown the invention embodied in several different circuits, but it is to be understood that I do 85 not limit myself to the embodiment shown in said drawings, since the invention, as set forth in the claims, may be embodied in a plurality of other forms.

Referring to said drawings:

Figure 1 is a diagrammatic representation of a receiving circuit embodying my invention.

Fig. 2 represents a like arrangement with the exception that the grid leak is shunted 100 around the condenser in the grid circuit.

Fig. 3 represents a modified form of circuit in which the controlling inductance in the grid circuit is coupled to the transformer secondary.

Fig. 4 represents a modified form of circuit in which the coupling between the grid circuit and the feed back circuit is continuously varied.

Fig. 5 represents a modified form of cir-

cuit in which the electrical time constants of the grid circuit are continuously varied by a revolving condenser.

Fig. 6 represents a modified form of circuit in which the feed back circuit is supplemented by an amplifier.

I have obtained loud and distinct signals with the circuit shown in Fig. 1 and shall describe such circuit in detail. In receiving signals from a given distant station, the signals produced in the telephones in my circuit are many times louder and more distinct than are produced in the telephones in other well known receiving systems which are now widely used. In experimentation, I have received the signals from a given distant station with my circuit and with the Armstrong circuit and in instances where the signals in the Armstrong circuit were barely perceptible, the signals produced in the telephones in my circuit could be distinctly heard many feet away.

The receiving system shown in Fig. 1 comprises the grounded antenna circuit containing the primary 3 of an oscillation transformer, the secondary 4 of which is connected as usual in the grid circuit, which circuit also contains the shunted variable capacity 5. Arranged in the circuit adjacent the grid 6 is a variable capacity 7. The other side of the grid circuit is connected to the filament 8 which is adapted to be heated by current from the battery 9, and a grid leak comprising the inductance 12 and the resistance 13 connects the grid with the other side of the circuit.

Arranged in the grid circuit, on that side of the secondary 4 remote from the grid 6, is a controlling variable inductance 14, shunted by a variable capacity 15 and by a circuit containing an interrupter 16 adapted to be driven at a speed sufficiently high to interrupt the circuit at a high frequency, within the range of audibility. Connected to and linked with the grid circuit, is the plate circuit, connected at one end to the plate 17 and at the other end of the filament 8 and containing the battery 18, telephone receiver 19, shunting condenser 21 and inductance 22 which is coupled to the primary 3 or secondary 4 of the oscillation transformer. This coupling should be sufficiently tight to cause the energy in the grid circuit to build up during the period of oscillation of the grid circuit, but not sufficiently tight to make the grid circuit a continuously oscillating circuit.

The impedance of the inductance 14 and the condenser 15, or the impedance of the inductance 14 alone (the use of the condenser 15 not being essential) is so chosen with relation to the values of the inductance 4 and the condenser 5, that the grid circuit does not oscillate when no signals are being received and when signals are received, does not os-

cillate when the interrupter 16 is open. This impedance value should preferably be high in order to stop the grid current flow when the interrupter is open, and with this condition existing no sound due to the interrupter is heard in the telephones. The signal intensity of the telephones is greatest when the value of the impedance is just sufficient to stop the sound of the interrupter in the telephones. 75

The system is not in oscillation until some external force, such as a received signal, acts on it, so that with the interrupter in operation and no signal being received, no sound is produced in the telephones. The received signal current acting in the circuit of the inductance 4, condenser 5, supplies sufficient electromotive force to cause the system to oscillate during the time that the interrupter is closed and the signal is produced in the telephones as the result of the plate circuit current changes that follow the change from a non-oscillating to an oscillating condition, and vice versa. The received signal current changes the circuit, when the interrupter is closed, from a non-oscillating condition to an oscillating condition and the opening of the interrupter changes it back to a non-oscillating condition. During the condition of oscillation, the oscillations produced in the plate circuit are effective, due to the coupling of the plate circuit with the grid circuit, to build up or amplify the energy in the grid circuit with the resultant amplification of the plate circuit current variations. Upon the opening of the interrupter, the condition of oscillation immediately and abruptly ceases. There is, therefore, produced, during the receipt, for instance, of a wave train representing a dash, a series of amplifications of grid circuit current with intervening abrupt collapses, producing loud and definite signals in the telephones. 100 105

The more nearly the impedance value of the element or elements short circuited by the interrupter is brought to the critical point where it is just sufficient to prevent oscillations when the interrupter is momentarily opened, the more easily do the incoming oscillations cause the system to oscillate and the signals are much stronger since the impedance permits the optimum grid current to flow, when the said grid current is not sufficient to cause oscillations in the system in the absence of the received signal current. 110 115 120

In the system shown in Fig. 1, I have obtained excellent results when the circuit is tuned to 18,000 meters with the following values of the constants in the circuit to wit— inductance 4, 240 millihenrys; inductance 22, 240 millihenrys; inductance 14, 1 henry; inductance 12, .8 henry; capacity 5, .0003 mf.; capacity 7, .0002 mf.; capacity 15, .0001 mf.; capacity 21, .006 mf.; resistance 13, 54,000 ohms; battery 18 of 40 volts. I do not de- 125 130

sire it to be understood that 13,000 meters is the only wave length that this circuit will effectively receive, since with these same values, signals of from 10,000 meters to 25,000 meters are readily received. In comparing signal strength between this system and heterodyne reception, using a standard and audibility meter, the ratio is about 1,000 to 1, that is, signals having an audibility value of 10 by the heterodyne system have an audibility value of 10,000 by the present system.

The present understanding and modes of explanation of the phenomena which present themselves in such an arrangement is such that any theory of operation which may be advanced in regard to them is merely an attempt to explain the results attained in language which will be understandable to those skilled in the art and I desire it to be understood that this invention is not to be limited by any statement of theory advanced herein, but is to be construed in the light of the results attained.

The circuit shown in Fig. 2 is similar to that shown in Fig. 1, with the exception that the grid leak 24 is shunted around the condenser 7 and the condenser 15 is omitted, the variation in impedance of the circuit being produced by the inductance 14 alone. In this figure the inductance 14 is shown as being provided with an iron core, but this is not essential, in fact, I believe the air core inductance to be productive of the better results.

The circuit shown in Fig. 3 is substantially the same as that shown in Fig. 2, with the exception that the inductance 14 is coupled to the secondary 4 of the oscillation transformer. With the interrupter rotating and a signal being received, the interrupter opens and closes the circuit of the inductance 14, thereby rapidly varying the electrical time constants of the grid circuit, and changing it from an oscillating condition to a non-oscillating condition. With the interrupter closed, the incoming signal will produce oscillations in the grid circuit, which are built up by the feed back inductance 22. When the interrupter opens the oscillations immediately and abruptly cease, causing a distinct signal in the telephones.

In the arrangement shown in Fig. 4, amplification of the received signal is accomplished by rapidly varying the coupling be-

tween the feed back inductance 22 and the secondary of the oscillation transformer, preferably by rotating the inductance at a high angular velocity. When the axes of the inductances 4 and 22 are in alinement, the current in the grid circuit is amplified and when the inductances are at right angles, no amplification occurs.

In the arrangement shown in Fig. 5, the controlling inductance 14 is shunted by a revolving condenser 25, the function of which is to vary the capacity between maximum and minimum values at a high rate. The value of the inductance is such that when the capacitance is a minimum, the circuit does not oscillate and when the capacitance is a maximum, the incoming oscillations are amplified to produce oscillations in the circuit. The circuit is thus rapidly converted from an oscillating condition to a non-oscillating condition and vice versa, at a frequency within the range of audibility.

In Fig. 6 I have shown a modified form of circuit, in which the feed back circuit is omitted. The secondary 4 of the oscillation transformer is connected to the grid of a thermo-ionic vacuum tube 26, which serves as an amplifier. The plate circuit of the amplifier tube contains the primary 27 of the oscillation transformer 28 and the battery 29, and amplified oscillations are produced in the plate circuit. The secondary 31 of the oscillation transformer 28 is connected to the grid of the thermo-ionic vacuum tube 32, the plate circuit of which tube contains the telephones 33 and the common battery 29. The grid circuit is provided, as in Fig. 1, with an inductance 34 which is shunted out of and into the grid circuit by the rotating interrupter or commutator 35.

I claim:

A radio receiving system, including a thermo-ionic vacuum tube, a grid circuit, a plate circuit inductively coupled with the grid circuit, said grid circuit being normally non-oscillatory, an inductance in the said grid circuit, the impedance of which is sufficiently high to stop the flow of current in the grid circuit and an interrupter shunting said inductance.

In testimony whereof, I have hereunto set my hand.

CHARLES V. LOGWOOD.
